UNITED STATES PATENT OFFICE

RANDOLPH F. HALL, OF ITHACA, NEW YORK, ASSIGNOR OF ONE-THIRD TO THEODORE P. HALL, OF WALLINGFORD, CONNECTICUT, AND OF ONE-SIXTH TO PAUL WILSON, OF ITHACA, NEW YORK.

AIRPLANE.

Application filed November 3, 1923. Serial No. 672,548.

To all whom it may concern:

Be it known that I, RANDOLPH F. HALL, a citizen of the United States of America, and a resident of Ithaca, county of Tompkins, State of New York, have invented certain new and useful Improvements in Airplanes, of which the following is a specification.

This invention relates to certain improvements in airplanes; and the nature and objects of the invention will be readily apparent to and understood by those skilled in the arts involved in the light of the following explanation and detailed description 15 of the accompanying drawings illustrating what I now believe to be the preferred embodiments or aerodynamical and mechanical expressions of the invention from among various other forms, arrangements, combinations and constructions of which the invention is capable within the spirit and scope thereof.

A type of airplane is generally adapted and intended for operation and use in a certain class of service and for performing certain operations, and is so designed as to develop a performance capable of fulfilling the operating requirements and meeting the operating conditions encountered in the class 30 of service for which the type is designed and intended. The performance of an airplane is dependent upon certain basic and fundamental factors, of which the type and resulting aerodynamic characteristics of the 35 supporting surface or wing employed is a controlling one, particularly with reference to the lifting capacity, climb, and speed range, including the landing speed, of the airplane. In the design of a type of airplane to develop a certain desired performance, a type and design of supporting surface or wing is employed having the requisite aerofoil section and curve, area, and shape, which with the other controlling 40 factors will result in the desired performance for the type.

An airplane so designed and having a performance adapted for certain classes of service and the attendant operating conditions, is not generally adapted or capable of operation with any degree of efficiency or safety for other classes of service under conditions requiring a performance other

than that for which designed, without changing or varying the factors upon which the designed performance is based and dependent; such for example, as substituting a supporting surface or wings of a different type having the requisite aerodynamical characteristics which together with the other factors will develop the desired performance. In the operation and use of airplanes it is frequently necessary or desirable to perform a certain class of service or certain operations calling for a performance of which the available types are not capable, as for example to decrease the landing speed, or to increase the lifting capacity of a type, where the available types could be rendered capable of the required performance by 65 substituting a supporting surface or wings of different aerodynamical characteristics to meet the requirements of the desired performance. However, to change the supporting surface or wings of an airplane and substitute wings of the desired characteristics therefor, is an operation requiring considerable time and expense, and results in a permanent change in the performance of the airplane, from the performance for 70 which designed and intended. Therefor, this manner of changing or modifying the performance of a type to meet the more or less emergency or temporary requirements for such changes encountered in service, is 75 not generally practical or feasible.

In attempts to fulfill the need for varying or changing the normal performance of an airplane to increase the range of possible services and operations of which it is capable, and to thereby meet the demands beyond or outside of the normal performance, which the type may encounter in operation and use, various types and designs of supporting surfaces or wings have been devised in which the performance controlling factors, such as the incidence, camber, and area, are variable to change the characteristics of the supporting surface or wing with the resulting change in the performance of an airplane to meet the desired operating conditions and requirements. However, the provision of a supporting surface or wing having variable characteristics necessitates a more or less complicated wing construction 95 and the provision of mechanism for operat- 100 105

ing the variable elements of the wing to change the characteristics thereof, with the resulting increase in the possibility of wing failure through breakage therein or in the 5 operating mechanism therefor. Further, wings of the variable characteristic type are not adapted to incorporation in or mounting on, or for substitution in place of, supporting surfaces or wings of conventional types 10 on an airplane, without removing such wings from the airplane, or completely and permanently redesigning and reconstructing the same and eliminating any possibility of readily and practically reconverting the 15 wings to the original type and design from which changed.

Therefore, one of the main objects of the 20 present invention is to provide for readily changing the performance of an airplane in order to adapt the same to meet and fulfill the operating requirements of services and operations beyond or outside of the performance for which originally designed and capable, by temporarily, or if desired permanently, varying or modifying the characteristics of the conventional types of supporting surfaces or wings of an airplane to develop the required performance without destroying or redesigning the original 25 construction and design of the wings, and in such a manner that the wings as varied or modified can be readily reconverted or changed back to the original design and characteristics.

30 A further object of the invention is to provide a unit structure adapted to be mounted on or incorporated with an airplane supporting surface or wing of conventional or other type and design, to vary or modify the controlling characteristics of the wing, such as the incidence, camber, or area, and thereby change or vary the resulting performance of the wing.

35 A further object of the invention is to provide a unit structure adapted to be detachably mounted on an airplane supporting surface or wing to vary or modify the controlling characteristics thereof and change the normal performance of the wing, without reconstructing or destroying the original wing construction or design, and which unit structure can be readily detached to reconvert the wing modified thereby to its original design and performance.

40 A further object of the invention is to provide a series of unit structures or panels having different characteristics and adapted to be readily mounted on and detached from the supporting surface or wings of an airplane to modify the performance controlling characteristics thereof and change the performance of the airplane, so that the 45 performance of an airplane in service can be readily and practically changed to meet the varying demands of service by attaching

the unit structures or panels to the wings having the necessary characteristics to develop therewith the required performance.

50 A further object of the invention is to provide for temporarily or permanently changing or modifying the aerofoil section of a supporting surface or wing of conventional or other type, without reconstructing or destroying the original construction and design thereof, so that a wing so modified can be readily reconverted to the original 55 design and section, if desired.

55 A further object of the invention is to provide as an accessory for airplanes, unit structures or panels adapted for detachable 60 mounting on the supporting surface or wings of an airplane to modify the wing characteristics and change the performance of the airplane and thus increase the service and operation range of which the airplane 65 is capable.

65 A further object of the invention is to provide means for modifying the characteristics of airplane supporting surfaces or wings, which is adapted to use with the conventional types and designs now in use, as well as with special designs constructed particularly for use with modifying means of the invention.

70 A further object of the invention is to increase the practical use of highly specialized airplane types, such as the high speed or racing type, by providing for the temporary modification of the wing characteristics of the type to develop the required 75 performance for practical service and operations, in such a manner that a modified wing can be readily reconverted to the original design and characteristics and permit operation of the type for the service for which 80 designed.

75 A further object of the invention is to develop a system of field or operating service for airplanes, by means of which the 85 wing characteristics of an airplane can be 80 readily and quickly temporarily modified in an efficient and safe manner, to develop a performance beyond or outside of that for which designed, to meet the emergency demands encountered in operation for a performance of which available types are not 90 capable.

85 With the foregoing and various other objects and results in view, which other objects and results will be readily recognized by those familiar with the aeronautical art from the following explanation, the invention consists in certain novel features in design and in the construction and combination of elements, as will be more fully and 95 particularly referred to and pointed out hereinafter.

90 Referring to the accompanying drawings:

95 Fig. 1 is a diagrammatical view in vertical transverse section through a conventional 100

wing with upper and lower panels embodying the invention in applied position thereon to modify the characteristics of the wing.

Fig. 2, is a diagrammatical view in vertical transverse section through a wing with a characteristic modifying unit of panel applied to the lower or under surface of the wing.

Fig. 3, is a diagrammatical view in transverse vertical section through a wing with a characteristic modifying unit or panel applied and mounted on the upper surface of the wing, a similar panel of a design such as not to change the area of the wing being indicated by dotted lines.

Fig. 4, is a diagrammatical view in transverse vertical section through a wing with a characteristic modifying super-structure embodying the invention built upon and applied to the upper and lower surfaces of the wing.

Fig. 5, is a vertical transverse section, more or less diagrammatical, through a wing of the metal type with a unit structure mounted on and applied to the upper surface thereof to modify the characteristics of the wing.

Fig. 6, is a diagrammatical view in vertical longitudinal section through a portion of a wing having a superstructure applied to the upper and lower surfaces of the wing to modify the characteristics thereof.

Fig. 7, is a detail view, more or less diagrammatical, in front elevation of a portion of the leading edge hinge connection of the panels shown in Fig. 1.

Fig. 8, is a detail diagrammatical view in side or end elevation of the hinge connection of Fig. 7, the leading edge portions of the panels being shown.

Fig. 9, is a detail diagrammatical view in side or end elevation of a trailing edge connection formed in one-piece and particularly adapted for use with the panels of the type of Fig. 1.

Fig. 10, is a detail diagrammatical view in side or end elevation of another form of leading edge connection for use with upper and lower panels of the type of Fig. 1.

Fig. 11, is a detail diagrammatical view in end or side elevation of a form of trailing edge connection similar to the leading edge connection of Fig. 10.

Fig. 12, is a detail transverse section taken on the line 12—12 of Fig. 5.

Fig. 13, is a detail diagrammatic view in end or side elevation of a trailing edge connection for a panel applied to the lower or under surface of a wing.

Fig. 14, is a diagrammatical front elevation of a more or less conventional type of biplane having the wing characteristics thereof modified by mounting panels on the upper surface of the upper wing and under surface of the lower wing to show the appli-

cation of the invention to an airplane without interfering with the normal rigging arrangement thereof.

Several aerodynamical expressions and embodiments of which the invention is capable are illustrated more or less diagrammatically in the accompanying drawings purely by way of example and not of limitation, for the purpose of explaining the broad principles and features presented by and included in the invention, so as to enable those skilled in the aeronautical art to understand the same. According to the broad principles of the invention as exemplified by the illustrated embodiments, the performance of an airplane is changed or varied by modifying the characteristics of the supporting surface or wings thereof, which may be of conventional or other design or type, without reconstructing or changing the design and mounting of the original supporting surface or wings, and further in such a manner that the supporting surface or wings as modified can be readily and quickly reconverted to the original characteristics and resulting performance from the airplane for which designed. This is accomplished by utilizing the supporting surface or wing to be modified as a base upon and from which a structure is detachably and removably mounted and supported to change those factors, such as the incidence, camber or area, upon which the aerodynamical characteristics and performance of the wing are dependent, and result in a modified supporting surface or wing to develop the desired performance.

One possible form and embodiment of the means for carrying out the invention is illustrated diagrammatically in Fig. 1 of the drawings as detachably applied to and mounted on a supporting surface or wing 10 of conventional or any other desired design and construction. In this form and aerodynamical expression of the invention a unit structure or panel 11 is applied on and extending over the upper surface of the wing 10, and a unit structure or panel 12 is applied on and extending over the lower or under surface of the wing 10. The upper and lower panels 11 and 12 are extended forwardly and rearwardly a distance beyond the leading and trailing edge portions of the wing 10 and are joined or meet to form the leading and trailing edges 14 and 15, respectively, of the modified wing. The outer surfaces 11^a and 12^a of the upper and lower unit structures or panels 11 and 12, respectively are curved or cambered chordwise of the wing, and are suitably inclined, curved, or otherwise shaped and formed longitudinally or spanwise of the wing, so as to develop the desired or required aerofoil section and shape in and for the modi-

fied wing formed by the base wing 10 and the panels 11 and 12 mounted and supported thereon.

The depth or thickness of the unit structures or panels 11 and 12, in connection with the depth or thickness of the original or base wing 10 to be modified, will determine the depth or thickness of the modified wing section, which can be formed of the required thickness for the performance desired, by utilizing panels having the proper depth, as will be readily apparent. In the present embodiment of the invention typified by the use of upper and lower unit structures or panels, not only the depth or thickness of the original or base wing 10 is modified, but another characteristic determining factor, the area, is modified, and the extent of this modification or increase in area is determined by the distance the panels are extended beyond the leading and trailing edges of the original or base wing 10, as well as by the distance, if any, which the panels may be extended beyond the tip of the base wing, and is further dependent to a small degree upon the depth or thickness of the unit structures or panels 11 and 12. In the illustrated example, the relative camber and incidence of the modified wing are approximately the same as and substantially follow and conform to the camber and incidence of the base or original wing 10 which is modified by the addition of the panels 11 and 12, with the result that the modified wing is a thick section wing of greater area than the original wing 10 but with substantially the same relative camber and incidence factors. However, it is to be understood, as will be apparent to those familiar with the aeronautical art, that the unit structures or panels 11 and 12 can be formed with any desired cambers and designed to provide any desired incidence when applied in mounted position on a base or original wing and develop a modified wing of the desired section and characteristics.

The wing modification units or panels 11 and 12 in the example of Fig. 1, are detachably and removably mounted and supported in position on and modifying the original wing 10, which forms a base therefor. Any suitable or desired means or mechanism and construction and arrangement thereof, may be utilized for detachably mounting the panels 11 and 12 on the wing 10, and in the present example removable bolts or tie rods 16 are disclosed extended through and traversing the upper and lower panels 11 and 12 and the original wing 10, to detachably secure the panels in mounted position on the wing 10. The bolts or tie rods 16 can be provided with the retaining nuts 16^a which are arranged to lie in countersunk bores or openings provided through the outer surface of the modification panels to

prevent interruption of such surfaces by the bolts or fastening nuts.

The upper and lower unit structures or panels 11 and 12 are preferably connected or coupled together at their meeting or joined ends which form the leading and trailing edges of the modified wing in mounted and applied position of the panels on the base or original wing 10. One manner of connecting and joining the meeting ends of the panels in mounted applied position is more or less diagrammatically disclosed in Fig. 1, in connection with the detail disclosures of Figs. 7 and 8. The meeting forward ends of the upper and lower panels 10 and 11, which form the leading edge 14 of the modified wing, are pivotally connected and joined by a hinge connection 17 which comprises, referring to Figs. 7 and 8 of the drawings, the hinge leaf forming members 17^a and 17^b fixed to and over the forward edges of the upper and lower panels 11 and 12, respectively, and pivotally coupled and connected by the hinge pin, rod or wire 17^c which extends through and is received by the opposite hinge leaf members 17^a and 17^b. With the forward or leading ends of the upper and lower panels thus pivotally connected and joined by the hinge connection 17, to apply the panels 10 and 11 to a wing to be modified they are swung open on the hinge connection to separated position and slipped over the leading edge onto the base or original wing 10 and then swung toward each other into mounted position on and over the upper and lower surfaces thereof. The panels are then fixed in mounted position by the removable bolts 16 or other securing means. If desired, any suitable trailing edge connection is detachably mounted on and connecting the extended rear or after meeting and joined ends of the panels 11 and 12 which form the trailing edge 15 of the modified wing, such for example, as the connection 18 diagrammatically indicated in Fig. 1 of the drawings. The trailing edge connection 18 can be in any of a number of forms and removably secured over the meeting ends of the panels, as by bolts, screws, rivets or other removable attaching means. In order to remove the panels 11 and 12 and convert the modified wing to the original design and characteristics presented by the base wing 10, the trailing edge connection 18, if employed, and the detachable securing bolts or tie rods 16 are removed, and the upper and lower panels are swung outwardly on the leading edge hinge connection 17 away from the base wing 10, and then slipped or lifted forwardly therefrom, thus converting the base wing 10 to the original design and characteristics.

The type of trailing edge connection dis-

closed in Fig. 1, is more or less diagrammatically illustrated in detail in Fig. 9, and comprises a one-piece substantially **V** or **U** shaped member or strip which is fitted over the meeting rear edges of the upper and lower panels 11 and 12 which form the trailing edge 15 of the modified wing. The trailing edge connection can be detachably secured on and connecting the panels by any suitable fastening means (not shown), such as bolts, rivets, screws or the like.

In Figs. 10 and 11 of the drawings, another type of leading and trailing edge connection is disclosed, and comprises a two-piece connection formed by members 18^a and 18^b secured or fixed along the leading or trailing edges of the upper and lower panels 11 and 12, respectively, and having outwardly bent and extended flanged portions which are detachably secured and connected together with the panels in mounted position on a base wing; by means of the removable bolts or the like 18^c. Fig. 10 shows this type of connection applied to the leading edge 14 of the panels, and Fig. 11 discloses the same applied to the trailing edge thereof.

Another type of trailing edge connection is shown in Fig. 13, which is particularly adapted for application with the type of upper panel 12' disclosed in Fig. 3 and described in detail hereinafter, and in the present form consists of a strip or bar 19 fixed along the under or lower side of the panel 12' adjacent to and spaced inwardly a distance from the trailing edge of the panel, by bolts, rivets or other desired fastening means 19^a. In fixed position the connecting strip 19, thus forms an angular or **V**-shape recess to receive the trailing edge of an original or base wing 10, as indicated in Fig. 13 of the drawings.

In Fig. 2 of the drawings an original or base wing 10 is modified to change the aerodynamical characteristics and resulting performance therefrom, in accordance with the principles of the invention, by the application and mounting of a modifying structure or panel 11' to the lower or under face or surface of the base wing 10. This structure or panel 11' is formed of the required thickness or depth and with the required camber to form with the thickness or depth and with the required camber or curvature of the upper surface, of the base wing 10, a modified wing of the desired section, camber, incidence, and area to develop the performance required. With the lower panel 11', the area of the original or base wing 10 is increased due to the extension of the forward and rear ends of the panel a distance beyond the leading and trailing edges respectively, of the base wing to form the leading and trailing edges 14 and 15 of the modified wing. The extended portions of

the panel 11' are suitably shaped and curved to merge into and form unbroken continuations of the upper cambered surface of the base wing 10. Any suitable or desired securing means, such as hereinbefore referred to, may be utilized for removably mounting and applying the modifying structure or panel 11 in position on the base wing 10, and in the illustrated example portions of removable bolts 16 are shown which extend through the panel 11' and are adapted to engage the base wing 10 and detachably secure the panel in position thereon.

An original or base wing 10 is illustrated in Fig. 3 of the drawings as modified by the detachable mounting thereon of an upper unit structure or panel 12' applied on and extending over the upper surface of the wing 10 to form therewith the modified wing having the desired characteristics to develop the performance desired. In this example of the invention, the modifying structure or panel 12' is formed to extend in mounted position a distance forwardly and rearwardly beyond the leading and trailing edges, respectively, of the base wing 10, to provide the leading and trailing edges 14 and 15 of the modified wing, and the under surfaces of the leading and trailing edge forming portions 14^a and 15^a are so curved as to merge with and form the proper forward and rear continuations, respectively, of the under surface of the base wing, to provide the required lower or under contour and camber for the modified wing, as will be clear by reference to Fig. 3 of the drawings. With the form of modifying structure or panel 12' the area of the original or base wing is increased in the modified wing resulting from the mounting of the panel thereon, and the camber and incidence can be modified to the desired degree by proper formation and shaping of the panel, as explained hereinbefore. However, where desired or necessary to secure the required modified performance, the modifying structures or panels of the invention, of the type of 12' or other types, can be formed for application and mounting on a base wing 10 without increasing the area thereof. An example of a panel so formed of the type of 12' is diagrammatically disclosed by dotted lines in Fig. 3, as a panel 12'' which in mounted position does not extend beyond the leading and trailing edges of the base wing 10 but has the forward and rear edges terminating at and merging with the leading and trailing edges of the base wing 10 to form therewith the leading and trailing edges 14' and 15', respectively, of the modified wing. By this design and formation of the modifying structure or panel, a modified wing is provided of the same area as the original or base wing from which formed. As in the case of the modifying

structures or panels previously described, any suitable or desired means, such as bolts, tie rods, rivets, or the like (not shown) can be employed for detachably mounting and securing the panels 12' and 12'' on and to the original or base wing 10.

The embodiments and aerodynamical adaptations presenting the principles of the invention, diagrammatically disclosed in Figs. 1 to 3 of the drawings and described as unit structures or panels, may be formed and constructed in any suitable or desired manner, as of a shell-like or hollow form, or of a frame-work upon which a skin or covering is applied to form the surface of the modified wing, and it is not intended or desired to in any way limit the invention to any particular form or construction.

As illustrative of another possible adaptation of the principles of the invention, a modified wing is purely diagrammatically illustrated in Fig. 4 of the accompanying drawings, as formed by a super-structure built or applied on and over an original or base wing 10 without reconstructing or destroying the original wing, which latter can be reconverted to its original form and design by removing the modifying superstructure therefrom. In the present example this modifying superstructure comprises a series of stringers or formers 20 extending longitudinally over the upper surface of the wing 10, and a similar series of longitudinal stringers extending over the lower surface of the wing. The stringers 20 of the upper and lower surfaces of the wing 10 are spaced apart chordwise thereof from the leading to the trailing edges of the wing, and the stringers or formers 20 of each series are of varying thickness or depth, respectively, to develop the desired depth or thickness and camber in the modified wing. Any suitable covering or skin 21 is fixed to and extending over and across the upper and lower series of longitudinal stringers or formers 20 and covering and enclosing the base or original wing 10. The upper and lower skin 21 thus forms the upper and lower surfaces of the modified wing, and are joined or meet at the leading and trailing edges, respectively of the modified wing. Thus, the base wing is modified by such superstructure to present a thicker section and if desired to provide a different camber and incidence from the base wing. The superstructure can be arranged and constructed to increase the area of the base wing, where desired, or can be arranged as shown in Fig. 4, so as not to increase the area. With such superstructure a supporting surface or wing can be modified without reconstructing or destroying the original or base wing, and when desired the superstructure can be readily removed to reconvert the modified wing to its original form and characteristics.

In Fig. 6 of the drawings a portion of a modified base or original wing 10 is diagrammatically disclosed in which a modifying superstructure of the type shown in Fig. 4 is employed. However, in the form of Fig. 6, transverse stringers or formers 20' are secured on and extending chordwise of the upper and lower surfaces of the original or base wing 10, and are spaced apart longitudinally or spanwise thereof. A covering or skin 21 is applied on and extending over the upper and lower series of transverse stringers 20', respectively, to complete and form the upper and lower surfaces of the modified wing, as hereinbefore explained.

The application of the invention to a supporting surface or wing of the metal type is more or less diagrammatically illustrated in Figs. 5 and 12 of the drawings, in which example the original or base wing 10' is specially and particularly constructed and arranged for use with and modification by means embodying the invention, although it is to be understood that the invention is adapted and applicable to use with any type of metal wing of the conventional or other forms and designs. The metal base or original wing 10', in the present instance is formed from a series of longitudinal, spaced U-section channel beams 30 having the base sides disposed at the upper side of the wing and the open sides thereof at the lower side of the wing. An upper metal skin 31, smooth or corrugated, is fixed over and extending across the upper closed or base sides of the beams 30, and a lower metal skin 32 is fixed over and extending across the lower open sides of the beams 30, which latter terminate in flanged portions to which the skin 32 is fixed in any suitable manner. The forward and rear end edges of the upper and lower skin or coverings 31 and 32 are joined and secured together in the usual manner to form the leading and trailing edges of the wing, as will be clear to those skilled in the art. If desired or found expedient, transverse metal stiffening ribs such as the rib 33 may be formed in the wing extending between the longitudinal beams 30.

A unit metal structure for modifying the original or base wing 10' in accordance with the invention is provided and formed, in the present instance to be detachably and removably mounted on the upper side of the original wing to form therewith a modified wing of the required characteristics. The unit metal modifying structure or panel 34 is in the present instance formed of a construction similar to that of the original or base wing 10', and includes the longitudinal U-section beams 30 which are disposed with their closed or base sides at the under or lower sides at the lower side of the unit structure and their open sides terminating in flanged portions over and

- to which a covering or skin 35 is fixed, in a manner similar to the skin 32 of the original wing 10'. In order to strengthen and stiffen the unit 34, transverse ribs 33 are fixed in and extending between the longitudinal beams 30, as hereinbefore referred to with reference to the similar ribs 33 in the original wing 10'. In the form of unit 34 disclosed herewith the under 10 or lower side thereof is uncovered and the longitudinal beams 30 are spaced a distance apart equal to the spacing of the similar beams 30 of wing 10', so that when the modifying unit is applied to and mounted 15 on the upper surface of wing 10', the closed or base sides of the beams 30 of unit 34 will rest upon the upper skin 31 directly above and alined with the beams 30, respectively of the wing 10'. 20 The metal original or base wing 10' is modified by applying the unit metal structure 34 on the upper side thereof with the beams 30 of the wing alined with the beams 30 of the unit, and the skin 35 of the unit 25 extending over the beams 30 thereof and suitably detachably connected at the forward and rear edges thereof to the leading and trailing edges of the original wing, so as to form therewith the leading and trailing 30 edges, respectively, of the modified wing. The forward and rear edges of the skin 35 can be detachably connected to the original wing, as by the leading edge hinge type of connection 17 having a removable hinge pin 35 or rod, and the use of removable bolts, rivets or the like (not shown) for securing the trailing edge. The skin 35 is, of course, mounted and secured over the beams 30, which are of the proper varying depths, 40 to secure the desired camber and contour of upper surface in the modified wing. The unit structure 34 is detachably secured in mounted position on the original or base wing 10' by spaced series of bolts 36 extending through the adjacent alined closed or base ends of the pairs of wing beams and unit structure beams 30, respectively, these bolts 36 extending through the upper skin 31 of the base wing 10' and firmly 45 50 55 60 65 70 75 80 85 90 95 100 105 110 115 120 125 130 removably attaching the unit structure 34 in position modifying the base or original wing, as clearly shown in Fig. 5 of the accompanying drawings. Openings or hand holes 37 are provided in and through the upper skin or covering 35 of the modifying unit 34, directly above the detachable securing bolts 36, respectively, so that said bolts are accessible for attaching and detaching the same to permit of securing and removing the modifying unit on and from the original or base wing 10'. Similar openings or hand holes 37, can be formed through the lower skin 32 of wing 10' for access therethrough to the lower end of 65 the securing bolts 36, or other attaching means, if found desirable or expedient. The openings 37 formed through the skin of the original wing and the modified wing can be suitably covered or closed to prevent air interference in flight, by removable fabric or the like patches (not shown) varnished or otherwise secured over and covering the openings, or by removable closure plates, (not shown), as will be readily understood.
- Attention is directed to the fact that in the adaptation of the invention disclosed in Fig. 5, the main elements, original wing and modifying unit, can be in effect reversed, by securing the upper skin 31 to the lower side of unit 34 to form a complete wing thereof, and leaving the upper side of wing 10' uncovered so as to form a unit modifying structure applicable for mounting on the lower or under side of a wing of the general type illustrated. Further, the modifying structure or panel, such for example as the upper unit 34 of Fig. 5, can be designed and formed to provide a wing by applying a lower skin thereon having the required contour or camber, and when applied to a wing such as 10' to modify the same, the lower skin of the unit is superposed upon the upper skin 31 of the original wing, thus in effect providing a wing formed of sections each of which provides a complete wing, the sections being separable or detachable to permit use of one thereof as a wing.
- As an illustration and example of the application and use of the principles of the invention, an airplane A of more or less conventional design embodying a biplane truss is disclosed diagrammatically in Fig. 14 of the drawings, as having the supporting surface or wings thereof modified in accordance with the invention. The airplane shown embodies a biplane truss comprising the upper and lower wings 10 and a bracing or rigging arrangement therefor formed by the struts or the like S, in the usual or any suitable manner familiar to those skilled in this art. The airplane A with the biplane wing truss will develop a certain performance which is dependent upon certain controlling factors, of which the characteristics of the upper and lower wings 10 form a major factor. The designed performance of the airplane A can, therefore, be changed by modifying or varying the characteristics of the wings to meet the requirements of the desired performance. In accordance with the invention the wings 10 of the airplane A are modified by the application and detachable or removable mounting thereon of suitable structure to change the characteristics of the wings to develop the required performance, without reconstructing or destroying the original wings 10, or of the bracing and rigging arrangement S thereof. In the

example illustrated the upper wings 10 are provided with the unit structures or modifying panels 11 applied and detachably mounted on the upper sides thereof, and the 5 lower wing 10 is provided with the unit structure or modifying panel 12 applied and detachably mounted on the lower or under side thereof. The panels 11 and 12 are designed and formed to cooperate with the upper and lower wings 10, respectively, to produce modified wings having the characteristics to develop the required performance for the airplane, as will be clear from the hereinbefore appearing explanation of the 10 invention and its application. By the arrangement of Fig. 14 it will be noted that the modifying structures 11 and 12 can be readily applied and mounted on the wings 10 without removing or reconstructing the 15 same, or without rearranging or removing the rigging thereof. When it is desired to reconvert the modified wings to their original design and characteristics, the modifying structure 11 and 12 is removed 20 and the airplane returned to its original performance. The application and removal of the modifying structure or panels to and from the wings of an airplane can be readily performed on the field without requiring 25 the services of other than available field personnel or the use of special equipment.

With the invention it is possible to readily change the performance of an airplane, without withdrawing the same from service, 30 to meet the requirements of a service beyond or outside of the performance range for which designed, by applying a modifying structure in accordance with the invention to the supporting surface of the airplane to form therewith a modified supporting surface having the necessary characteristics. After completion of the service for which 35 modified, the modifying structure can be readily removed from the supporting surface of the airplane and reduce or reconvert the same to the original design and characteristics. The invention is of particular value for use with airplanes of the various 40 types in service where it may be desired to temporarily or permanently employ a type for certain operations for which the designed performance is not efficiently capable, as for example, where it is desired to increase the lifting capacity or reduce the landing speed. 45

example of a type to meet the requirements of a certain service. Further, by the invention it is possible to convert special types, such as racing or high speed airplanes, to practical and general utility by modifying the supporting surfaces thereof to increase the lifting capacity and reducing the landing speed. Again, in cases of unsatisfactory performance the application of modifying structure embodying the invention can be employed to vary or change the supporting surface

characteristics to effect a possible remedy.

The invention contemplates and provides for the formation of a series of modifying structures or panels having different characteristics for use with a type of supporting surface and mounting thereof, each structure when applied to the supporting surface forming a modified surface having different characteristics and resulting performance, so that a type may be operated over a wide range of services by selecting and applying the modifying structure which with the original supporting surface will develop the required characteristics. In this manner field service can be developed for airplanes which will permit of their being readily and quickly converted to develop the required performances to meet the exigencies of service requirements and operating conditions. The modifying structures for a type can be furnished with each airplane by the manufacturer as accessories therefor, or a service can be maintained from which operators can secure the desired modifying structures.

While the accompanying drawings diagrammatically disclose embodiments of the invention applied to the wings of an airplane, it is to be understood as will be readily recognized by those skilled in the aeronautical art, that the invention and principles involved are equally adapted to use on other performance controlling elements, such as the control surfaces of an airplane. The modifying structure, units or panels diagrammatically presented herewith as extending completely over and covering a side or sides of a supporting surface are merely for purposes of explanation and not by way of limitation, and it is desired to call attention to the fact that the invention contemplates and includes any form of element or structure applied to a supporting or control surface for modifying the characteristics thereof, irrespective of whether the structure completely covers the surface in either a chordwise or a spanwise direction.

Attention is directed to the fact that the modification structures or units are designed and intended where necessary to reinforce the strength of the original or base wing upon which mounted, so that the resulting modified wing will possess the requisite factor of safety to care for additional loads which may be imposed thereon.

The term "structure" or the term "panel", wherever they appear in the appended claims are employed in a broad, generic sense to include any form and design of construction or arrangement for application to a supporting or control surface to modify the characteristics thereof.

It is further evident that various changes, modifications, variations and substitutions might be resorted to, and hence it is not desired or intended to limit

the invention to the exact disclosures hereof.

Desiring to protect my invention in the broadest manner legally possible, what I claim is:

5 1. In combination with an aerofoil, a temporary rigid unit structure fixed over a surface thereof to modify the aerodynamical characteristics of the aerofoil, the aerofoil forming a support therefor, the said rigid unit structure completely detachable and removable from the aerofoil.

10 2. In combination with an aerofoil, a temporary structure thereon enclosing the aerofoil to form therewith a modified aerofoil having different characteristics.

15 3. As an accessory for airplanes, a series of unit structures each constructed and arranged to be removably mounted on and cooperate with a supporting surface of an airplane to modify the performance thereof, and each of said structures modifying the supporting surface to develop a different performance, respectively, from the airplane.

20 4. In combination with an airplane wing of the metal type embodying a series of wing beams enclosed within a skin, a unit modifying structure including a series of beams having a skin extending thereover across one side thereof, the said unit structure mounted on one side of said wing with the beams thereof vertically aligned with the wing beams and the skin thereof outermost to form a modified wing, means detachably connecting said aligned beams, and means detachably securing the ends of the skin of said unit to said wing.

25 5. A panel constructed and arranged to be mounted on an aerofoil extending over a surface thereof and presenting an outer surface cooperating with the aerofoil surfaces to form a modified aerofoil therewith, the inner side of said panel open and arranged to fit over and be closed by an aerofoil on which mounted.

30 6. A panel constructed and arranged to be mounted on an aerofoil extending over a surface thereof and presenting an outer surface merging into the leading and trailing edges of the aerofoil and cooperating with the aerofoil surfaces to form a modified aerofoil, the inner side of said panel open and closed by the surface of an aerofoil on which mounted.

35 7. In combination, an airplane including a main performance controlling supporting surface having aerodynamical characteristics to develop a predetermined performance for the airplane, a substantially rigid temporary structure mounted in fixed position on said supporting surface and cooperating therewith to form a modified supporting surface capable of developing a different performance for the airplane, and said temporary structure completely removable from

40 convert the main supporting surface to its original characteristic and performance.

8. In combination with an airplane including a performance determining main supporting surface having non-variable aerodynamical characteristics to develop a predetermined performance for the airplane, a temporary performance modifying accessory embodying a substantially rigid structure mounted in fixed relation on and supported by said supporting surface without major structural change in the latter, the said structure arranged and constructed to form with the said supporting surface a modified supporting surface having aerodynamical characteristics to develop a different performance for the airplane, and the said structure detachable and completely removable from the supporting surface and the airplane, the said supporting surface with said temporary structure removed converted to its original characteristics and the airplane to its original performance.

45 9. In combination with an airplane including a performance determining main supporting surface having non-variable aerodynamical characteristics to develop a predetermined performance for the airplane, a temporary performance modifying accessory embodying a preformed unit structure mounted in fixed relation fitting onto and supported by said supporting surface without structural modification of the said supporting surface, the said unit structure arranged and constructed with the outer surface thereof cooperating with the supporting surface to form a modified supporting surface for the airplane having different characteristics and a modified performance, and the said unit structure completely removable from the supporting surface and the airplane, the said supporting surface converted to its original characteristics and structural unity with the unit structure removed without reconstruction of the said supporting surface.

50 10. In combination with an airplane including a performance determining main supporting surface having non-variable aerodynamical characteristics to develop a predetermined performance for the airplane, and exterior trussing from one side of said supporting surface; a temporary structure mounted in fixed relation on the side of said supporting surface opposite said trussing and unobstructed thereby, the said structure arranged and constructed to form with said supporting surface a modified supporting surface capable of developing a different performance for the airplane, and said temporary structure completely removable from the supporting surface and the airplane to convert the supporting surface to its original characteristics without structural modification thereof.

11. In combination with an airplane including a supporting surface of the multiplane type formed of wings having non-variable characteristics to develop a predetermined performance for the airplane, a temporary structure mounted in fixed position on each wing without structural change in the wings, each of said temporary structures arranged and constructed to form with 5 the wing on which mounted a modified wing having different characteristics and the modified wings forming a multiplane supporting surface developing a different performance for the airplane, and each of said temporary structures removable completely from the 10 wing on which mounted to convert the wing to its original characteristics and change the multiplane supporting surface formed of said wings to develop the original performance for the airplane.
12. In combination with an airplane of the biplane type including upper and lower wings of the non-variable characteristic type to develop a predetermined performance for the airplane, and trussing extending between said wings; a temporary structure mounted in fixed position on the upper surface of the upper wing, and a temporary structure mounted in fixed position on the 15 lower surface of the lower wing, each of said temporary structures arranged and constructed to cooperate and form with the wing on which mounted a modified wing having different characteristics, and said 20 temporary structures formed with respect to each other so that the resulting modified wings provide a biplane supporting surface capable of developing a different performance for the airplane, the said temporary 25 structures completely removable from said wings and the airplane to convert the wings to their original characteristics without structural change therein.
13. A characteristic modifying structure 30 for aerofoils, embodying a pair of panels constructed and arranged to fit over the upper and lower surfaces, respectively, of an aerofoil and to form therewith an aerofoil of different characteristics in mounted position of the panels, and means for detachably securing said panels in mounted position on an aerofoil.
14. A characteristic and performance 35 modifying structure for an aerofoil, embodying a panel constructed and arranged to fit over the upper surface of an aerofoil, a panel constructed and arranged to fit over the lower surface of the aerofoil, said panels of greater chord than the chord of the aerofoil and in mounted position on the aerofoil forming a modified aerofoil therewith, and means for detachably connecting the forward and rear edge portions of said panels in mounted position thereof to define the 40 leading and trailing edges of the modified aerofoil.
15. As a new article of manufacture, a performance modifying accessory for airplanes, embodying a complete substantially rigid unit structure specifically designed for use with an airplane wing of given form and characteristics, the said complete unit structure constructed and arranged to fit on and be supported by the wing without structural modification in the wing and in mounted position fixed with respect to the wing in cooperative relation therewith forming a modified wing of different characteristics, the said unit structure completely removable from a wing without structural change in the latter, and means for detachably fixing said unit structure on a wing, the said means removable with said structure from a wing on which mounted.
16. As a new article of manufacture, a performance modifying accessory for airplanes, embodying a unit structure for application to a given airplane wing having non-variable aerodynamical characteristics, the said unit structure consisting of a frame formed on one side to fit over and receive a surface of the given wing and covered on the other side by a skin having a camber to cooperate and form with the wing on which mounted a modified wing of different characteristics, and means for removably fixing said unit structure on the given wing, said structure completely removable as a unit from the given wing on which mounted without structural change in the wing.
17. As a new article of manufacture, a performance modifying accessory for airplanes, embodying a unit structure specifically designed for use with an airplane supporting surface of given form and characteristics, said unit structure formed to be mounted in fixed position on the supporting surface in cooperative relation therewith to form a modified supporting surface of different characteristics, the said unit structure completely detachable and removable from a supporting surface to convert the surface to its original form and characteristics, and means for removably fixing said unit structure in position on a supporting surface to modify the characteristics thereof.
18. As an accessory for airplanes, a series of performance modifying unit structures specifically designed for use with an airplane supporting surface of given form and characteristics, each of said unit structures formed to be mounted in fixed position on the supporting surface in cooperative relation therewith to form a modified supporting surface of predetermined characteristics, the said unit structures in mounted position each forming with the supporting surface.

a modified surface of different characteristics, respectively, each unit structure completely removable from the supporting surface on which mounted to convert said surface to its original characteristics, and means for removably fixing any desired one of said unit structures to the given supporting surface.

19. In combination with an aerofoil, a panel detachably mounted thereon to form a

modified aerofoil therewith, the said panel of greater chord than the aerofoil and having the forward and rear portions thereof extending beyond the aerofoil formed to provide the leading and trailing edges of 15

Signed at Ithaca, New York, this 29th day of October, 1923.

RANDOLPH F. HALL.
